UNITED STATES PATENT OFFICE.

PAUL L. CROWE, OF JERSEY CITY, NEW JERSEY.

UNDERFEED STOKER.

976,047.

Specification of Letters Patent. Patented Nov. 15, 1910.

Application filed October 5, 1907. Serial No. 396,091.

To all whom it may concern:

Be it known that I, PAUL L. CROWE, a citizen of the United States, and resident of Jersey City, in the county of Hudson and State of New Jersey, have invented certain new and useful Improvements in Underfeed Stokers, of which the following is a specification.

This invention relates to automatic combined underfeed and overfeed stokers, and the object is to provide this class of stokers with certain mechanical means of conveying the fuel to the furnace and also in means for agitating the same.

Another object is in the means of conveying the air from the conduits or air chambers into the burning mass.

Another object is in means for operating the dumping ash-grate.

Another object is in means for supplying air to the fuel chutes.

Referring to the drawings: Figure 1 is a front view of a furnace stoker embodying my invention. Fig. 2 is a longitudinal sectional elevation. Fig. 3 is a side elevation of a section of the furnace wall showing the mechanism for operating the pusher and dump grate. Fig. 4 is a detached cross section of three of the fuel chutes on line Y Y, Fig. 2, the pushers therein being taken at different sections, and one blower only shown. Fig. 5 is a detached cross section of two of the fuel chutes on lines Y^a, Y^a, showing the flanges at the lower portion for uniting them together. Fig. 6 is a perspective view showing part of two fuel chutes, the section showing air chamber and fastening means. Fig. 7 is a detached enlarged front view of the ash dumping grate mechanism. Fig. 8 is a detached front view of two or more blocks composing the arch.

The furnace 2 consists of a combustion chamber 3, a bridge wall 4, a boiler 5, and steam drum 6. The fuel chutes are supported within the furnace on an incline. There are a plurality of these chutes, and they lie close to each other, and are bolted together by bolts passing through flanges 7^a, formed integral with said chutes. This mode of construction gives rigidity and support to the combined structure.

10 is the air space under each chute. These spaces communicate with each other when the chutes are assembled. This communication is effected by forming a transversely disposed conduit 17, below each

chute. These conduits are formed at substantially the same distance from the upper ends of the chutes so that when the chutes are assembled a continuous air passage is formed the entire distance across the furnace, providing for a distribution of air from one air space to the remaining spaces.

The bottom casing of the air conduit is cut away at intervals to form openings under each chute over which is mounted a blower or fan casing 12. In each is located a fan rigidly mounted on a shaft 13 extending along the bottom of the furnace, chutes and conduit, and is driven by any motor. By this construction air is forced into the air passages. The air passages are made large through the blowers to permit of the use of natural draft when the blowers are not in motion.

The upper edges 7^a of the fuel chutes support the twyer blocks 8 which are so formed that when in position an opening 9 will be left between the blocks and the edges of the chutes. Each twyer block is provided with a central downwardly extending web, shaped to the inclined sides of the chutes, the downwardly extending and flaring portion of the web serving to retain them in position. Each chute has a pusher 18 which is continuously tapered from its upper or head portion down to the lower end and this tapered portion of the pusher on its upper side is flat, and on its under side is V shaped to conform more readily to the V shape of the bottom of the chute, and also to permit said pusher to more easily move up and down within said chute.

The object in forming the pushers with a continuous straight taper is to cause them to more evenly distribute the fuel in the chute, and also to more evenly break the crust of the burning fuel. Each pusher at the upper or head portion may be provided with a projection 20, and beyond this point it extends through an aperture outside the furnace. The under side of the extended portion is provided with rack teeth, and into the teeth mesh the pinion 22 on rocking shaft 23, suitably mounted. This rocking shaft is operated by an eccentric 24 connected to wheel 25, mounted on stud 26 outside the wall of furnace, and suitably driven by belt 28, over wheel 25 and pulley 29 on blower shaft 13.

31 is the dump grate journaled on shaft 32 which is supported on the flanges of the

2

chutes. There is one grate to a chute. The grate is locked up in position by the detent or dog 33 pivoted to the dump grate frame below the shaft 32. The upper member of the dog is formed at right angles to fit over and against the square sides of the shaft 32, which when turned by the eccentric or otherwise will raise or lower the dump grate. Over the pushers within the chutes is placed 10 the arch 52, mounted in the side walls of the furnace. This arch is composed of bricks 50 (see Figs. 2 and 8) which are on their lower side slightly inclined upward and inward, and also crown and flat shaped. 15 This arch in connection with the pushers aids the ignition of the fuel as it enters the hopper and passes down the chute, thereby producing smokeless combustion.

What I claim is:

- 20 1. The combination of a furnace, a plurality of similarly disposed fuel chutes mounted within the furnace said chutes being so constructed and connected that inclosed air spaces are formed between adjacent chutes when they are assembled adapted to provide a passage of air to the fuel a casing extending transversely beneath the chutes providing communications between the said air spaces, the casing being provided with openings located between adjacent fuel chutes and a separate fan mounted on the casing delivering air to each of said openings.
- 25 2. The combination of a furnace a plurality of fuel chutes mounted in said furnace inclining from the front to the rear, a reciprocating fuel pusher mounted to move in each of said chutes, each pusher tapered from its upper to its lower end and means 30 for feeding fuel to the upper ends of the chutes.
- 35 3. In a furnace, similarly disposed fuel chutes, V-shaped in cross section, mounted on an incline in said furnace, pushers mounted within said chutes, said pushers tapering from the upper to the lower end, and having a V-shaped under side which conforms 40 to the V-shape of the chutes, and means for operating said pushers.

4. The combination of a furnace, a plurality of fuel chutes mounted within said furnace inclining from the front to the rear, said chutes each having flanges provided with openings for receiving bolts to secure said chutes together, a shaft mounted on the flanges of said chutes, a dump grate journaled on said shaft, said shaft having flat sides a detent or dog pivoted on said dump plate below the said shaft, said dog having a right angle portion, said right angle portion adapted to fit over and against the flat sides of said shaft, and means for operating said shaft.

5. The combination of a furnace, a plurality of fuel chutes having apertures, said chutes mounted in said furnace inclining from the front to the rear, a reciprocating fuel pusher mounted to move in each of the chutes each pusher tapered from its upper to its lower end, each pusher provided with an extended upper portion extending through an aperture in said furnace rack-teeth formed on the underside of the projecting portion of said pusher a shaft said shaft mounted on said chutes, a pinion mounted on said shaft, said pinion provided with teeth adapted to mesh into the rack teeth of the said pusher and means for rocking said shaft.

6. The combination of a furnace, a plurality of inclined fuel chutes mounted in said furnace, each of said chutes provided with flanged plates forming air casings between the chutes and a connecting passage between the said casings when the chutes are as 85 sembed, means for connecting the flanges, said plates having a plurality of air intake openings at their flanged portions, a plurality of fan blowers mounted on the chutes at each intake opening and a shaft for operating said blowers.

Signed at Jersey City, in the county of Hudson and State of New Jersey this 3rd day of October A. D. 1907.

PAUL L. CROWE.
